UNITED STATES PATENT OFFICE.

HARRY DEL MAR, OF NEW YORK, N. Y., ASSIGNOR TO BOILER AND ENGINEERING COMPANY, OF JERSEY CITY, NEW JERSEY, A CORPORATION OF NEW JERSEY.

BOILER.

No. 855,446.

Specification of Letters Patent.

Patented June 4, 1907.

Application filed January 2, 1907. Serial No. 350,501.

To all whom it may concern:

Be it known that I, HARRY DEL MAR, of the city, county, and State of New York, have invented a new and Improved Fire-Tube and Water-Tube Boiler, of which the following is a full, clear, and exact description.

My invention relates to improvements in fire tube and water tube boilers, and the object of my invention is to produce a combination boiler possessing both the fire tube and water tube characteristics, which is exceedingly compact, has the principal fire tubes submerged, has a series of water tubes and headers surrounding the main drum in such a way as to utilize the heat from the products of combustion to the best advantage, and which in general is a quick and efficient steam making boiler. By combining the fire tubes and water tubes in a boiler, the water tubes will give out before the drum can burst in the event of carelessness, or for any other cause beyond the control of the man in charge of the boiler. A boiler of this type, too, can be made to cover more ground space and less height than the ordinary vertical boiler, and besides greater power can be put in a small space, and steam can be produced quicker and of a drier quality than with the ordinary vertical boiler.

Another object of my invention is to produce a boiler having the gases of combustion which pass through the first set of fire tubes returned in an opposite direction through the set of fire tubes in the annular steam drum, so as to make this part of the boiler a return fire tube element and prevent the waste of heat which results from a direct course through the fire tube system. The water tube system has a set of baffle plates to direct the course of the gases, and besides the tubes can be staggered so as to break up the gases and utilize the heat to the best advantage.

With these ends in view, and with the general object of producing a boiler which will make steam economically, my invention consists of certain features of construction and combinations of parts which will be hereinafter described and claimed.

Reference is to be had to the accompanying drawing forming a part of this specification, in which similar letters and figures of

reference indicate corresponding parts in all the views.

Figure 1 is a central vertical section of a boiler showing my improvements. Fig. 2 is a sectional plan on the line 2. 2 of Fig. 1, and Fig. 3 is a sectional plan on the line 3. 3 of Fig. 1.

The design of the boiler is not very material, and I have shown a design which illustrates the use of the combination fire tubes and water tubes, but these can be arranged in many other ways without departing from the principle of the invention, as will be readily seen from the description which follows.

The boiler has a main water drum 10, which merges at the top into a larger and partly surrounding drum 11, and obviously the relative height of these parts can be changed to suit varying circumstances. The drum 11 has a depressed central portion 12, the bottom of which forms the top of the drum 10, so that the fire tubes 13 which extend longitudinally through the drum 10 can be constantly submerged. Any number of these tubes 13 can be used, and they extend the full length of the drum 10, as shown in Fig. 1. Return fire tubes 14 are also arranged in the drum 11, and extend from the space in the top of the boiler to the circular flue 15, from which connection can be made with the stack at any desired point and in any usual way. The boiler is provided with a suitable casing 16, the walls of which merge into the outer wall of the flue 15. It will be seen that the hot gases will rise through the tubes 13, be deflected by the top of the casing 16, and pass down the tubes 14. It will also be observed that this structure makes a complete fire tube boiler, but I prefer to use the surrounding water tubes and connections which will be described below.

Radiating from the lower part of the drum 10 but not quite all around it, are tubes 17 and 18, which are staggered so that the tubes 18 will not be in vertical alinement with the tubes 17, and these connect the drum 10 with headers 19, which latter can be of any approved form either straight or serpentine. The reason for leaving a part of the drum blank so far as the arrangement of tubes and headers is concerned, is to afford firing space as shown clearly in Fig. 3. The headers 19

connect by nipples 20 with the mud drums 21, which as shown by dotted lines in Fig. 3, form preferably segments of a circle, and the drums connect by tubes 22 with the drum 10. 5 Above the lower headers and above the tubes 17 and 18 are series of tubes 23 and 24 which are also staggered, and which extend from the upper part of the drum 10 to the headers 25, and these, which may be of any approved 10 type, entirely surround the drum 10, being preferably in a circular group as shown in Fig. 2. The headers 25 are, however, preferably just inside the headers 19, so that the tops of the latter can be easily reached, and 15 the headers 19 should have caps 26 on the top as shown in Fig. 1, and by removing the caps, and by having the headers offset as shown, one is enabled to reach down through the headers 19 to clean the nipples 20, or to 20 do any work thereon. Opposite the several radiating water tubes, and in the outer walls of the headers, removable caps 27 can be arranged as shown on one of the headers in Fig. 2, so that ready access can be had to the wa- 25 ter tubes.

From the foregoing description it will be seen that I provide a very simple and highly efficient boiler, which is a combination of fire tubes and water tubes, that the hot gases of 30 combustion will rise through the tubes 13 and pass down and out through the tubes 14, while a part of the hot gases will also rise between the several water tubes, and so I provide a boiler having water tube and fire tube

features in a very compact form and in a man- 35 ner to economize heat.

It will be obvious that the design can be changed materially without affecting the in- vention.

Having thus fully described my invention, 40 I claim as new and desire to secure by Letters Patent:—

1. A boiler of the kind described, comprising a main drum having fire tubes extending longitudinally through it, water headers 45 placed around the main drum, water tubes connecting the headers with the main drum, and mud drums placed around the main drum and connected with the main drum and with the water headers. 50

2. A boiler of the kind described, comprising a main body portion having an enlarged steam drum, up-take fire tubes leading through the boiler proper, down-take fire tubes leading through the steam drum, upper 55 and lower water headers arranged around the boiler, mud drums below the water headers, and connections between the boiler proper, the headers, and the mud drums.

3. The combination with the fire tube and 60 water tube boiler, of superposed series of wa- ter tube headers, arranged around and forming the side walls of the boiler, the said head- ers connecting by water tubes with the boiler.

HARRY DEL MAR.
